UNITED STATES PATENT OFFICE

2,484,154

ILLUMINATED FOUNTAIN PEN

John J. Devine, Middletown, Conn.

Application May 10, 1946, Serial No. 668,859

1 Claim. (Cl. 240—6.46)

1

This invention relates to fountain pens and is more particularly directed to a means for providing illumination during writing.

An object of the invention is the provision of an illuminated fountain pen in which a circuit to a lamp carried by the pen is closed when a battery mounted in one end of the barrel of said pen is moved rearwardly in said barrel.

Another object of the invention is the provision of an illuminated fountain pen in which a spring forming one element of the switch is in contact with the inner electrode of a battery housed in one end of a metal barrel of the pen, a second element of said switch being adjacent the spring and in conductive relation with a filament of a lamp adjacent the pen point, the metal barrel being in conductive relation between the other electrode of the battery and said filament, said spring being so arranged that when the battery is moved rearwardly in said barrel, it will move into engagement with the second mentioned element of the switch and close the circuit to the lamp.

A further object of the invention is the provision of an illuminated fountain pen having an electric lamp surrounding the support for the pen point, said pen including a metal barrel housing a battery at one end and the pen structure at the other end, a curved spring forming one element of a switch being normally compressed by the inner electrode of the battery and maintained out of contact with a second switch element which is connected with the filament of said lamp, the barrel being in conductive relation between the other electrode of the battery and said filament, rearward movement of the battery permitting the curved spring to contact both the inner electrode of the battery and the second switch element for closing the circuit to the filament.

The invention consists in the novel construction, arrangement and combinations of parts hereinafter more particularly described and claimed.

In the drawings:

Figure 1 is a longitudinal vertical section of a pen constructed according to the principles of my invention;

Figure 2 is a side view in elevation of an electric lamp employed in connection with the pen but removed therefrom;

Figure 3 is a front view in elevation of the lamp shown in Figure 2.

Figure 4 is a transverse vertical section taken along the line 4—4 of Figure 1;

2

Figure 5 is a transverse vertical section taken along the line 5—5 of Figure 1.

Figure 6 is a view in perspective of a switch element removed from the barrel of the pen, and

Figure 7 is a transverse vertical section taken along the line 7—7 of Figure 1.

Figure 8 is a sectional view illustrating the connection between the ink sack and ink conveying tube.

Referring more particularly to the drawings, 10 designates a metal barrel forming a housing for the various elements of the pen structure. A cap 11 is threaded onto the rear end of the barrel and maintains a battery 12 in a predetermined position. The other end of said barrel carries the pen structure.

An electric lamp 13 is circular and surrounds a cylinder 14 within which there is a hard rubber tube 14', a compressible sack 16 being secured at one end. The opposite end of the tube 14' is slightly tapered permitting expansion under insertion of a plug body of the pen 15. Ink is stored in the sack and is fed through the tube 14' to the point. An opening 17 in the barrel 10 permits the insertion of an instrument for compressing said sack for causing refilling of the sack.

A collar 18 is located adjacent the inner end of the barrel. Notches 19 on the collar receive lugs 20 projecting from the barrel. A base 21 of the lamp 13 has a threaded sleeve 22 screwed into the barrel and secures the collar in place against the lugs 20.

The lamp 13 embracing the tube 14 forms substantially a closure for the inner end of the barrel 10. A filament 25 of said lamp is connected to the battery 12 by a wire 26 (Figure 5), the threaded sleeve 22 and the metal barrel 10.

A disk 27 mounted in the collar 18 has a central opening 28 to receive and support the tube 14 of the pen structure. A slot 29 permits the insertion of a contact tongue so as to have operative engagement with a contact of the lamp 13.

A switch for controlling the circuit to the lamp 13 includes a curved compressible spring 30 which has one end secured to the inner wall of the barrel 10 by plastic rivets 31. A strip 32 of insulating material is disposed between said spring end and the barrel. The free end 33 of said spring is in flat contact with the inner pole 34 of the battery 12 at all times. A curved portion 35 between the ends of the spring is compressed to the greatest degree when the cap 11 is screwed fully inward on the barrel 10.

55 A switch element 36 extends laterally from a

bar 37 formed of conductive material. The bar is spaced from the inner wall of the barrel 10 by an insulating strip 38 but is secured to said wall by plastic rivets 39. The bar is bent inwardly as at 40, and has a tongue 41 slightly roughened to engage a contact 42 projecting from the inner end of the base 21 of the lamp 13 when said lamp is screwed into positive position at the inner end of the barrel 10.

The parts of the pen are shown in position 10 in Figure 1, for writing but the bulb 13 is not illuminated. When the cap 11 is partially unscrewed to the dotted line position the spring 30 will move the battery rearwardly towards the partially unscrewed cap and will assume the dotted line position so that said spring will contact the switch element 36 and close the circuit to the lamp. It must be borne in mind that the free end 33 of the spring will always remain in contact with the pole 34 of the battery 12.

The circuit is closed through the bar 37, the contact 42, the filament 25, wire 26, sleeve 22, the barrel 10 and the casing of the battery which is in contact with said barrel.

When the cap is screwed completely on the barrel the portion 35 of the spring 30 will be moved away from the contact 36 for opening the circuit to the lamp.

Although a preferred and practicable embodiment of the invention is disclosed herein, it is to be understood that various modifications may be made within the scope of the appended claim.

I claim:

In an illuminated fountain pen, a barrel hav-

ing a threaded end, the other end mounting an electric bulb adjacent the pen point, a battery within the barrel, a cap engaged on the threaded end of the barrel and maintaining the battery in a pre-determined position, a circuit including the battery, bulb and barrel, a spring forming a switch element mounted in the barrel and having a laterally disposed bight provided with a free end disposed centrally of the barrel for engaging and pressing upon a centrally disposed contact of the battery, a second switch element carried in the barrel and insulated therefrom positioned rearwardly of and in the path of movement of the bight of the first mentioned switch element, said second switch element being electrically connected to said bulb whereby a partial unthreading of said cap permits the spring to move the battery rearwardly to engage the first and second named switch elements.
